MEANS FOR CIRCULATING FLUIDS

Kemper P. Brace and Robert B. P. Crawford,
Washington, D. C.

Application April 19, 1935, Serial No. 17,368

7 Claims. (Cl. 62—119.5)

This invention deals with the forced circulation of fluids and more particularly with the propulsion of one liquid into another under a higher pressure without the employment of pumps or other mechanical moving parts. An object of the invention is to provide a method and apparatus for continuously concentrating a solution which is being continuously diluted and for continuously diluting a solution which is being continuously concentrated thereby maintaining the degree of concentration substantially constant.

A further more specific object is to provide a method and means for supplying liquid to a boiler without the use of a pump or other mechanical moving mechanism.

A still further more specific object is to provide a method and apparatus for pumping the liquid in an absorber type of refrigerator from the absorber into the boiler without the use of mechanical pumps and without the use of hydrogen or other gases commonly used to balance the pressures in systems of this kind.

Further objects and advantages will become apparent as the description proceeds.

Referring to the accompanying drawings which are made a part hereof and on which similar reference characters are used to denote the same part throughout,

Figure 1 is a view in elevation of one of the simplest forms of apparatus embodying the invention.

Figure 2 is a view in elevation of a refrigerating system of the absorber type showing the application of the invention.

Figures 3 and 4 are modified forms of refrigerating apparatus showing the invention.

It is well known that if a pure solvent is separated from a solution of a solute in the same solvent by a semi-permeable membrane, there will be a flow of solvent thru the membrane into the solution. This flow will occur even when the pressure upon the solution is much greater than the pressure upon the solvent. The pressure necessary to be applied to the solution to prevent this flow is called the osmotic pressure of the solution. As would be expected, the osmotic pressure of any solution depends upon the concentration of the solution, that is, the higher the concentration, the higher the osmotic pressure. For solutions of non-electrolytes such as cane sugar, the osmotic pressure is equal to the pressure which an equivalent gram molecular volume of the solute would exert if confined to the space occupied by the solution. Due to the effect of ionization, the osmotic pressure of electrolytes such as NaCl, NaOH, LiCl, etc., is as a rule considerably higher than that of non-electrolytes of the same concentration. It has been found that for any substance, whether it is an electrolyte or

a non-electrolyte, the osmotic pressure of a solute in a solution is a function of the vapor pressure lowering caused by the solute in the solution. The equation connecting the lowering of the vapor pressure and the osmotic pressure is as follows:

$$P = \frac{R \cdot T}{18 S} \left(\frac{p_0 - p}{p_0} + \frac{1}{2} \frac{(p_0 - p)^2}{p_0} + \frac{1}{3} \frac{(p_0 - p)^3}{p_0} \right)$$

where P=Osmotic pressure in atmospheres

R=Gas constant=82.07

T=Absolute temperature

S=Specific volume of the solvent at P

p₀=Vapor pressure of the pure solvent

p=Vapor pressure of the solution.

From the above formula it can be readily seen that the osmotic pressure of any solution which is of sufficient concentration to lower the vapor pressure appreciably of the solvent is very high. For example, the osmotic pressure of a six molar (67%) sugar solution is 232 atmospheres or 3410 lbs. per square inch whereas the vapor pressure lowering of a six molar sugar solution

$$\frac{(p_0 - p)}{p_0}$$

is only 20% at 70 degrees F.

The fact that the osmotic pressure of a six molar sugar solution is equal to 3410 lbs. per square inch means that if a semi-permeable membrane separates the solution from pure solvent, that is, from pure water, a pressure of 3410 lbs. per square inch would have to be applied to the solution to prevent water from passing thru the membrane into the solution.

If instead of separating a solution from a pure solvent, a solution is separated from a stronger solution by means of a semi-permeable membrane, there will be a flow of pure solvent from the weaker solution to the stronger and the pressure causing the flow is equal to the difference between the osmotic pressures of the two solutions. The flow will continue until the concentration of the two solutions is the same, that is until both solutions have the same osmotic pressure.

Now if the stronger solution is continually concentrated by boiling off the solvent and the weaker solution is continually diluted by the addition of pure solvent, then the flow of pure solvent thru the membrane from the weaker solution to the strong solution will continue as long as there is a difference in concentration.

Figure 1 shows one of the simplest embodiments of the invention in the form of apparatus for continuously concentrating a solution which is being continuously diluted and for diluting a solution which is being continuously concentrated. Vessels 10 and 11 contain weak solution 12 and strong solution 13 respectively of some non-volatile solute in a suitable solvent, such for

example as cane sugar in water. The solutions are separated by a semi-permeable membrane 15. Pure solvent may be boiled off from the strong solution 13 by heating element 14, thereby concentrating the solution and pure solvent may be supplied by pipe 16 to the solution 12 to dilute this weak solution. So long as the concentration of the solution 13 is greater than the concentration of the solution 12 there will be a flow of pure solvent thru the semi-permeable membrane from chamber 10 into chamber 11.

We may assume that the solution 12 is a 1.0 molar solution of cane sugar in water and that the solution 13 is a six molar solution of cane sugar in water. The osmotic pressure of a six molar solution is 3410 lbs. per square inch. The osmotic pressure of a 1.0 molar solution is 397 lbs. per square inch. Therefore, the force driving pure solvent (water) from the weak solution 12 into the strong solution 13 is 3410 minus 397 lbs. per square inch or 3013 lbs. per square inch, and nothing will stop the flow of solvent from the weak into the strong solution except an external pressure on the strong solution of 3013 lbs. per square inch. It is apparent from the foregoing that a semi-permeable membrane provides means for causing a solvent to flow from a weak solution under a low pressure to a strong solution under a high pressure without the aid of a mechanical pump. Pressure may be built up in the boiler by providing a throttling valve 17.

From the structure described it will be apparent that the device may have many possibilities in its adaptation to useful purposes. For example, if the vapor under pressure from the boiler is conducted to a fluid motor the device may serve as a boiler for an engine in which the boiler is fed without the use of mechanical pumps or injectors.

Figure 2 shows the invention adapted to a refrigerating system of the absorber type. In this form of refrigerator a vapor is absorbed into a solution. As here shown numeral 18 indicates an evaporator, 19 an absorber, 20 a boiler, 21 a condenser, 22 a vapor conducting connection from the boiler to the condenser and 23 a connection from the condenser to the evaporator. Vapor is boiled off by a heater 24. A cooling coil 25 cools the liquid in the absorber. This cooling coil may be supplied with cooling water which passes thru pipe 26 to the condenser after leaving coils 25. If preferred both the cooler 25 and the condenser may be air cooled; such cooling systems are well known and therefore need not be here described.

Before starting, the boiler will be partially filled with a suitable solution. This may be a solution of cane sugar and water as stated in the description of the system shown in Figure 1, or a solution of any suitable non-volatile solute, such as NaOH, LiCl, H₂SO₄, LiI, ZnCl, etc., in a solvent.

Numeral 27 indicates the strong solution in the boiler, 28 a weak solution in the absorber and 29 the pure solvent in the evaporator. There will be a body of solvent vapor 30 above the body of solvent in the evaporator. The upper portion of the evaporator communicates with the upper portion of the absorber thru a passage 31. A semi-permeable membrane 32 separates the strong solution 27 in the boiler from the weak solution 28 in the absorber. Suitable examples of such membranes are collodion, parchment, animal intestine, animal bladder, fish skin, rubber, copper ferrocyanide precipitated in porous earthenware, porcelain, ground glass, gelatine, etc.

After filling the system to the desired levels

with the solutions and solvent, all air and other foreign gases are evacuated from the system and the system closed. The evaporator will be surrounded by or in heat exchange relation with the media to be cooled. Heat extracted from this medium will evaporate the refrigerant. Now the vapor pressure above the pure solvent 29 is greater than the vapor pressure above the weak solution 28. There will therefore be a flow of vapor from chamber 18 thru channel 31 into chamber 19, this vapor being absorbed into the solution 28. This evaporation of vapor from the solvent body 29 and absorption into 28 will cause the temperature in 18 to fall and the temperature in 19 to rise. The added heat in solution 28 may be carried off by the cooling coil 25. The addition of pure solvent to the weak solution 28 will tend to dilute this solution. But the solution in the boiler 20 is stronger than the solution 28. There will, therefore, be a flow of pure solvent 20 thru the semi-permeable membrane 32 from the body of solution 28 into the solution 27. The heater 24 continuously boiling off pure solvent from the solution 27 continuously concentrates this solution. The addition of pure solvent from absorber 19 will tend to keep the solution at the same degree of concentration.

The rate of flow of pure solvent from 19 to 20 is directly proportional to the difference between the osmotic pressures of the solutions 27 and 28 30 minus the difference in total pressure in vessels 19 and 20. Thus if the solution 28 is a 1.0 molar sugar solution having an osmotic pressure of 397 lbs. per square inch and solution 27 is a 6 molar sugar solution having an osmotic pressure of 3410 35 lbs. per square inch and if the pressure above the two liquids be ignored for the present, there will be a difference in pressures of 3410 minus 397, or 3013 lbs. per square inch and this will represent the force driving the pure solvent from solution 20 40 into solution 27.

For practical purposes a solution of sodium hydroxide (NaOH) and water is preferable to the cane sugar solution. Let us assume, therefore, that water and NaOH are the solvent and the 45 solute respectively. Let us assume that the temperature desired in the evaporator is 40 degrees F. and that the temperature of the tap water for cooling coil 25 is 70 degrees. Now the vapor pressure of water at 40 degrees is 6.4 mm. of Hg and 50 therefore in order for the water 29 in the evaporator 18 to boil at 40°, the vapor pressure of the solution 28 in the absorber 19 must be less than 6.4 mm. of Hg at a temperature slightly in excess of 70 degrees (say perhaps 80 degrees). Experimental data show that the vapor pressure of a 40% solution of NaOH in water exerts a vapor pressure of 5.3 mm. of Hg. at 80°. Therefore, we can assume that the concentration of the solution 28 is 40% and that the driving force causing 60 solvent vapor (water) to pass from 18 to 19 as 6.4-5.3, that is as 1.1 mm. of mercury. With an unrestricted passage 31 between the chamber 18 and the chamber 19 water vapor will pass at a rapid rate from 29 to 28 and the temperature of 65 29 will be maintained at 40 degrees as long as the temperature of the solution 28 is kept at 80 degrees and the concentration at 40%.

In order to maintain the concentration at 40% pure solvent must pass thru the semi-permeable 70 membrane as fast as solvent vapor passes from 29 to 28. In order to maintain this osmotic flow of pure solvent from weak solution 28 into strong solution 27 the concentration of 27 must be much greater than 28. Let us assume that the concen- 75

tration of 27 is 50% by weight. By the formula given, the osmotic pressure of a 40% solution 28 at 80 degrees F. is 28,300 lbs. per square inch. The osmotic pressure of a 50% solution 27 at 165 degrees F. (B. P. at 36 mm. Hg) is 35,750 lbs. per square inch. The difference between the osmotic pressure of solution 27 and solution 28 is 7,450 lbs. per square inch. Experimental data indicate that the amount of semi-permeable membrane required for a 100 lb. ice box is five square feet.

Figure 3 shows a form of the invention in which an interchanger 40 is positioned between the concentrator and the absorber. It will be noted that there is a temperature difference of about 85 degrees between the concentrator and the absorber. It is advisable to prevent a loss of heat from the concentrator to the absorber. The interchanger is designed to reduce the heat loss as far as possible, and thereby increase the efficiency of the system. Numerals 41, 42, 43 and 44 denote the condenser, the evaporator, the absorber and the concentrator or boiler. The evaporator contains pure solvent 45, the absorber contains weak solution 46 and the boiler a strong solution 47. Solvent is boiled off by heater 49. Cooling water for the cooler 48 is supplied thru pipe 50 the water leaving thru pipe 51 after passing thru the condenser 41 to condense the vapor from the boiler. Both cooler 48 and condenser 41 may be air cooled if desired.

The upper portion of the evaporator chamber is connected by pipe 52 with a pipe 53 which extends down into the weak solution 46 and terminates in a header 54 which is perforated to permit vapor to pass into the solution 46 and be absorbed therein. The absorber is connected by pipes 55 and 56 with a chamber 57 thru which the weak solution is circulated by convection. A chamber 58 is positioned within the chamber 57 and its walls are formed partially from semi-permeable membranous material 59. The strong solution in the boiler is circulated thru the chamber 58 passing from the boiler thru pipe 63 thence thru the interchanger 40, pipe 60, pipe 61, back thru the interchanger 40 and pipe 62 into the boiler. A water jacket 64 may be placed about the pipe 60 to cool the strong solution before it enters the chamber 58. This jacket may be supplied with water from the coil or water cooling jacket 48.

The heater may include a flue 67 which passes up thru the boiler to effect better heating.

Refrigerant vapor driven off the boiler passes thru pipe 65, condenser 41 and into receiver 66. In order to insure that only liquid refrigerant shall pass from the receiver to the evaporator a valve 68 operated by a float 69 controls passage of refrigerant to the evaporator.

Any suitable refrigerant may be used. For domestic refrigerators requiring evaporator temperature of 20 degrees or lower it is believed the most satisfactory solution would be a solution of ammonium thiocyanate (NH₄CNS) in liquid ammonia (NH₃).

Let us assume that the temperature desired in the evaporator is 15 degrees F. and that the temperature of the tap water or cooling air, when air is used, is 90 degrees. We will assume that the cooler 48 is large enough to maintain a temperature of 100 degrees in the weak solution 46. We will assume also that the cooling water in passing thru the cooler 48 is heated to approximately 100 degrees and that it is effective to condense the

ammonia in the condenser at a temperature of 110 degrees.

Now the vapor pressure of pure ammonia 45 in the evaporator 42 at 15 degrees F. is 2100 mm. of Hg. In order to have a flow of vapor from the evaporator to the absorber the vapor pressure of the weak absorbing solution must be less than the vapor pressure of the pure solution. The vapor pressure of a 60% solution of NH₄CNS in ammonia at 100 degrees F. is approximately 2000 10 mm. of Hg. This gives us a vapor pressure difference between the evaporator and the absorber of 100 mm. of Hg. We may therefore assume that the weak solution 46 is a 60% solution of NH₄CNS in NH₃. According to the formula the 15 osmotic pressure of a 60% solution of NH₄CNS in NH₃ at 100 degrees F. is 40,719 lbs. per square inch. Assume that the strong solution 47 in the boiler is an 80% solution of NH₄CNS in NH₃. From the formula we note that the 20 osmotic pressure of an 80% solution of NH₄CNS in NH₃ at 100 degrees F. is 49,677 lbs. per square inch. It should be noted that the strong solution which is circulated from the boiler is cooled by the jacket 64 and by the body of weak solution at 100 degrees temperature which surrounds the chamber 58.

Now as we have stated above, the vapor pressure above the weak solution 46 is 2000 mm. of Hg or about 38 lbs. per square inch. The vapor pressure above the strong solution is the vapor pressure of pure ammonia at condenser temperature, which as we have stated is 110 degrees F. This vapor pressure is about 250 lbs. per square inch. The force tending to drive pure ammonia 35 liquid from the weak solution into the strong is (49,677 + 38) - (40,719 + 250) = 8746 lbs. per square inch

It is therefore apparent that in spite of the pressure difference of 212 lbs. in the boiler and the absorber pure liquid will flow from the absorber into the boiler at a rapid rate thru the semi-permeable membrane due to osmotic force.

Figure 4 shows another embodiment of the invention. Numerals 70, 71 and 72 represent the evaporator, the boiler and the absorber. The absorber consists of a plurality of tubes having walls of semi-permeable membranous material connecting headers 91 and 92. This absorber is positioned in a chamber 73 where it is enveloped in vapor passing from the evaporator thru passage 74. The solution circulating by convection thru the absorber is cooled by air cooler 75 of any suitable sort. Pure solvent vapor in chamber 55 73 will be absorbed thru the walls of the tubes and will tend to dilute the solution therein. To maintain the proper degree of concentration in the tubes, a portion of the solution is circulated thru the boiler thru pipes 77, 78 and interchanger 79. This circulating solution is cooled by air cooler 76. This pipe 78 may be coiled around the flue 80 to effect better heating.

The boiler will be partially filled with a suitable solution. This may be a 60% solution of NH₄CNS in NH₃. The pure solvent in the evaporator may be liquid ammonia 82. Ammonia vapor boiled off from the boiler will pass thru pipe 83, be condensed by air condenser 83 and delivered to receiver 84. A valve 85 controlled by bellows 86 will control passage of liquid from pipe 87 to pipe 89 so as to prevent the passage of gas to the evaporator. Pressure in the bellows and pressure below the valve will be equal since both are subject to the pressure in the condenser 75

thru pipes 87 and 88 so that the valve 85 will be closed by gravity. When liquid accumulates in the leg 94 of the U-tube this will unbalance the valve and permit liquid refrigerant to pass thru the valve into the line 89.

Instead of the pressure operated valve just described we may use the float controlled valve shown in Figure 3.

Assume that a temperature of 15 degrees F. is desired in the evaporator and that the cooling media for the absorber is at a 90 degree temperature and that the coolers are sufficiently large to maintain a temperature of 100 degrees in the absorption solution and a temperature of 110 degrees in the condenser. We will assume, as stated above, that the solution 81 is a 60% solution of NH₄CNS in NH₃. Now, as we have stated, the vapor pressure of pure ammonia at 15 degrees is 2100 mm. of Hg. The vapor pressure of a 60% solution of NH₄CNS in NH₃ at 100 degrees F. is 2000 mm. of Hg. The osmotic pressure of a 60% solution of NH₄CNS in NH₃ is 40,719 lbs. per square inch. Since there is a pressure in the absorber chamber 13 outside the tubes of about 25 38 lbs. per square inch the total force tending to drive the pure solvent into the solution thru the semi-permeable membrane is 40,757 lbs. per square inch. But the vapor pressure of the pure ammonia in the condenser is the vapor pressure 30 at a temperature of 110 degrees which is about 250 lbs. per square inch. Taking this from the pressure indicated above, since this is a pressure acting against the flow of solvent into the strong solution, we have a total pressure acting to drive 35 solvent vapor into the solution of 40,507 lbs. per square inch.

From the foregoing it will be apparent that we have a system in which the solvent will be automatically supplied to the boiler and that the system will operate continuously without the necessity of a pump or the presence of an inert gas to balance pressures.

It will be obvious to those skilled in the art that various changes may be made in the invention without departing from the spirit thereof. We, therefore, do not limit ourselves to the invention as shown in the drawings and as described in the specification but only as set forth in the appended claims.

50 What we claim is:

1. A device of the kind described comprising a vessel having a compartment therein having a solution of a pure solvent and a nonvolatile solute dissolved therein, a second compartment having 55 a body of pure solvent therein under a pressure less than that in the first named compartment, a semi-permeable membrane separating the two bodies of liquid to cause a flow of solvent by osmosis into the solution, means for boiling off 60 solvent from the solution and means for supplying pure liquid solvent to the body of pure solvent.

2. A device of the kind described comprising a vessel divided into two chambers by a semi-permeable membrane, a concentrated solution of a solvent and a nonvolatile solute in one chamber, a less concentrated solution of the composition in the other chamber, and a third chamber having 70 a body of pure solvent therein, the space above said last named solvent being open to the space above the weaker solution to permit passage of vapor from said solvent to the said solution to be absorbed therein, the semi-permeable membrane

causing osmotic flow of pure solvent from the weaker to the stronger solution.

3. A refrigerator of the absorber type comprising a boiler, an absorber, an evaporator, a condenser and heater, the boiler having therein a strong solution of a solvent and a non-volatile solute, the absorber having therein a weaker solution of the same solvent and solute, means for conducting vapor from the evaporator into the weaker solution to have it absorbed therein, means for circulating said weak solution and for cooling it, a semi-permeable membrane separating the weak from the strong solution, means for circulating said strong solution in surface contact with said membrane to circulate the pure solvent absorbed from the weaker solution and bring it into the boiler to dilute the solution therein which is being continuously concentrated by boiling off pure solvent therefrom.

4. A refrigerator of the absorber type comprising a boiler, an evaporator, an absorber, a plurality of tubes positioned in the said absorber, said tubes being filled with a solution of a solute and a solvent, said tubes being exposed to solvent vapor from the evaporator, said tubes having 20 walls of semi-permeable membranes to cause the solvent to flow by osmosis from the absorber to the solution, means for carrying off heat from the solution, and means for circulating said solution thru the boiler, and means for boiling off 30 pure solvent from the solution, for condensing it and returning it in liquid form to the evaporator.

5. A refrigerating system of the absorber type comprising a still, an absorber, an evaporator, a condenser, and a semi-permeable membrane separating vapor of the pure solvent in the evaporator from solution circulated from the still, a liquid trap between the condenser and evaporator, and a pressure controlled balanced valve operable upon a rise of liquid in the trap for returning only liquid refrigerant to the evaporator.

6. A device of the kind described comprising a pair of chambers, one containing a solution of a volatile solvent and a non-volatile solute, the other containing a body of the solvent substantially free of the solute and under a pressure less than the pressure in the first named chamber, a semi-permeable membrane separating the solution from vapor of the body of pure solvent, and means for vaporizing solvent from the solution 45 in the first named chamber, condensing it, and delivering it to the body of solvent in the other chamber, the said membrane causing pure solvent to flow by osmosis from the body of pure solvent to the solution.

7. A refrigerating system of the kind described comprising a boiler containing a solution of a solute and a volatile solvent, a chamber, having walls of semi-permeable membranous material, in communication with the solution in the boiler, thermal means for circulating the solution from the boiler thru the said chamber, an evaporator, means for boiling off vapor from the solution, condensing it and delivering it to the said evaporator, means for conducting refrigerant vapor from said evaporator into surface contact with said semi-permeable membranous walls while maintaining said vapor under pressure appreciably lower than the pressure in said chamber, the solvent vapor being caused to flow by osmosis only thru the 60 semi-permeable membranous walls of the said chamber into the solution in said chamber.

KEMPER P. BRACE,
